UNITED STATES PATENT OFFICE.

WILLIAM C. WATSON, OF PATERSON, NEW JERSEY, ASSIGNOR OF ONE-HALF
TO THEODORE Y. KINNE, OF SAME PLACE.

CAR-COUPING.

SPECIFICATION forming part of Letters Patent No. 397,674, dated February 12, 1889.

Application filed September 13, 1888. Serial No. 285,293. (No model.)

To all whom it may concern:

Be it known that I, WILLIAM C. WATSON, of Paterson, in the county of Passaic and State of New Jersey, have invented a certain 5 new and useful Improvement in Car-Couplings, of which the following is a specification.

I will describe a car-coupling in detail, embodying my improvement, and then point out 10 the novel features in the claims.

In the accompanying drawings, Figure 1 is a vertical section of portions of cars and a coupling embodying my improvement. Fig. 2 is a horizontal section of the coupling. Fig. 15 3 is a similar view showing two cars in dotted outline and the position of the coupling due to the movement of the cars. Fig. 4 is a bottom plan of one member of the coupling. Fig. 5 is an end view of a car, showing one 20 member of a coupling embodying my improvement. Fig. 6 is a similar view showing the parts in different position from that shown in Fig. 5. Fig. 7 is still another similar view showing the parts in a third position.

25 Similar letters of reference designate corresponding parts in all the figures.

A designates the draw-heads. These draw-heads are of frame-like construction, and are hollow. They are capable of movement in 30 the direction of the length of the car, and are guided in such movement by means of guides *a* upon the bottom of the car. I have shown their rear ends as provided with turn-buckles. These turn-buckles bear near their rear ends 35 coiled springs, which bear against a portion of the turn-buckles and also against a guide, *a'*, secured upon the bottom of the car, and through which the rear portions of the turn-buckles are adapted to slide. These springs 40 offer resistance to the backward movement of the draw-heads.

B designates the coupling-hooks. These coupling-hooks are wholly contained within the draw-heads. They are pivoted near their 45 rear ends upon pivots *b*, which pivots are mounted in the draw-heads. Springs *C*, connected near one of their ends to the rear portions of the coupling-hooks and bearing near their other ends against the inner side of the 50 draw-heads, tend to force the coupling-hooks

into such position that they will engage upon two adjacent cars, or into such position that their engagement will be impossible.

In my coupling it is impossible for the coupling-hooks to abut end to end, and the hooks 55 also occupy three different positions. In the first of such positions they may be readily coupled. In the second of such positions they will, when two cars are brought together, pass by each other upon one side without 60 coupling, and in the third of such positions they will, upon the coming of two cars together, pass each other upon their rear sides without coupling. When two cars have been coupled together, they cannot be uncoupled 65 except the member of the coupling upon each of the cars be operated.

In the position of the coupling illustrated in Fig. 5, if two cars be brought together, a coupling will be effected such as is more 70 clearly illustrated in Figs. 2 and 3, the tendency of the spring *C* being to maintain the members in such coupling position. When thus coupled, as will be more clearly seen by reference to Fig. 3, a very wide range of lateral movement may be permitted to the cars 75 without in any way affecting the coupling or endangering its detachment.

When it is desired to uncouple the cars, the coupling-hooks are rocked out of engagement 80 against the resistance of the springs *C*. They may be rocked so far against the resistance of the springs that if the two cars were again brought together the faces of the hooks would pass by each other without engaging the 85 hooks. I have illustrated this position more clearly in Fig. 7. The movement of the hooks in such direction is effected by means of a lever, *D*, here shown as cross-shaped, or provided with four arms. This lever is fulcrumed 90 upon the end of the car. One of its arms extends upwardly above the car, so that the lever can be rocked from above, and its other two arms extend laterally to the sides of the car, so that the lever may be rocked from 95 either side. The other or downwardly-extending arm of the lever is pivotally connected to a slider-bar, *D'*, working in bearings *d* upon the ends of the car. This slider-bar is provided with the downwardly-extending arm 100

D^2 , which arm extends near its lower end through a suitably-formed aperture in an outwardly-extending portion of a pull rod or plate, D^3 . This pull-rod works through bearings in the sides of the draw-heads. When the lever D is shifted into either of the positions illustrated in Figs. 5, 6, and 7, the slider-bar D' , through the medium of the arm D^2 , causes a longitudinal movement of the pull-rod D^3 , whereby the coupling-hook is shifted to one side or the other.

In order to maintain the coupling-hooks in their three several positions, I employ a locking device, E. This locking device, in the present example of my improvement, consists of a rocking arm pivoted about midway in its length to the end of the car. This arm is provided on its under side with teeth e e' . The upper side of the slider-bar D' , near the end thereof which is adjacent to the end of the rocking arm bearing the tooth e' , is provided with a tooth, e^2 . The other end of the slider-bar D' , or that portion which is adjacent to the end of the rocking arm bearing the teeth e , is provided with a tooth, e^3 . The rocking arm E, as shown, is provided near its extremities with projections or handles e^4 e^5 . When these handles are grasped, the arm may be rocked in either direction and from either side of the car. Assuming that the projection or handle e^5 be grasped and the arm be rocked downwardly at that end, the tooth e' will be brought into engagement with the tooth e^2 , the spring C operating to throw the slider-bar into a position where such an engagement will be effected. The parts will then occupy the position illustrated more clearly in Fig. 5, or, in other words, will be in coupling position. If the projection or handle e^5 be grasped and that end of the arm E be moved upwardly, so as to cause a disengagement of the teeth e' e^2 , the slider-bar will be moved along, by the action of the spring C, into the position shown in Fig. 6. If this operation shall have been performed upon both cars, it will be clearly seen that should the two cars come together the backs of the coupling-hooks will pass by each other without effecting an engagement of the hooks. In order to restore the coupling-hooks from the position last named to a coupling position, or to bring them into such a position that the faces of the hooks will pass by each other should two cars be brought together, it is necessary to shift the coupling-hooks against the resistance of the spring C by means of the lever D. This, as has been previously stated, may be effected either by operating the lever D from above or from the sides of the car. If the lever be grasped and moved, it will occupy substantially the position shown in Fig. 5. The rocking arm E may of course be moved into such position as to again engage the teeth e' e^2 and to maintain the coupling-hooks in a locking position. If a still more extended movement of the

lever D be effected and the hook be moved into the position shown more clearly in Fig. 7, the teeth e e^3 will become engaged and the coupling-hooks will be maintained in such a position that their faces will pass by each other without effecting an engagement. The engagement of the teeth e e^3 may be effected by means of a weight, e^6 , upon the adjacent end of the arm E, which will cause the rocking of said arm in such direction as to cause the engagement of said teeth.

It will be seen from the foregoing that the springs C tend to throw the coupling-hooks into two of their positions, and that in the other of their positions they are maintained against the resistance of the springs C by the rocking arm E. It will also be seen that into any of the positions into which the coupling-hooks may be adjusted such adjustment may be effected either from the sides or the top of the car, and therefore it is unnecessary for a brakeman to pass in between the cars to either couple or uncouple them. It is to be observed, also, that when the coupling-hooks occupy the position shown in Fig. 5—or, in other words, are in their coupling position—and the two cars are brought together the deflection of the coupling-hooks necessary to cause their engagement will cause such a movement of the slider-bar D' as will release the teeth e' e^2 . The slider-bar, and consequently the coupling-hooks, will then of course be permitted to move freely in either direction and to assume a position analogous to that shown in Fig. 3, being always maintained firmly coupled by means of the springs C.

What I claim as my invention, and desire to secure by Letters Patent, is—

1. In a car-coupling, the combination, with a draw-head, of a coupling-hook within the draw-head, a spring for moving the coupling-hook in one direction, a slider-bar, a pull-rod, a connection between the slider-bar and the pull-rod, and a lever for moving the slider-bar, substantially as specified.

2. In a car-coupling, the combination, with a draw-head, of a coupling-hook within the draw-head, a spring for moving the coupling-hook in one direction, a slider-bar, a pull-rod, a connection between the slider-bar and the pull-rod, a lever for operating the slider-bar, and a stop for maintaining the slider-bar in a position into which it may be adjusted, substantially as specified.

3. In a car-coupling, the combination, with a draw-head, of a coupling-hook within the draw-head, a spring for moving the coupling-hook in one direction, a slider-bar, a pull-rod, a connection between the slider-bar and the pull-rod, a lever for operating the slider-bar, and a stop having portions extending to opposite sides of the car and adapted to engage either of the end portions of the slider-bar to maintain the latter in a position into which it may be adjusted, substantially as specified.

4. In a car-coupling, the combination, with
a draw-head, of a coupling-hook within the
draw-head, a spring for moving the coupling-
hook in one direction, a slider-bar, a pull-rod,
5 a connection between the pull-rod and the
slider-bar, and a lever for operating the slider-
bar, said lever having projections extending

to opposite sides of the car and a projection
extending above the car, substantially as
specified.

WILLIAM C. WATSON.
